UNITED STATES PATENT OFFICE.

FRED RICKS, OF LEICESTER, ENGLAND, ASSIGNOR TO UNITED SHOE MACHINERY CORPORATION, OF PATERSON, NEW JERSEY, A CORPORATION OF NEW JERSEY.

ART OF MANUFACTURING SHOE STIFFENERS.

Application filed March 28, 1925, Serial No. 19,160, and in Great Britain April 11, 1924.

This invention relates to the making of stiffened parts of boot and shoe uppers and is herein described in connection with the stiffening of the toe portions of the uppers 55 of boots and shoes.

Of recent years there has come into use a type of box toe blank, the thermoplastic box toe blank first described in United States Letters Patent No. 1,070,406, granted Aug. 10, 1913, upon an application filed in the name of Frank E. Butterfield, which, owing to its many advantages, has largely displaced the types formerly in use. The very 15 property, however, of this type of box toe blank which renders it so advantageous, namely its ability to soften merely by heating and to set immediately it cools, is one that brings with it in certain circumstances some likelihood of trouble for the shoe manufacturer. For example, if a shoe made 20 with such a box toe blank be exposed in a shop window to an unusual degree of summer heat too soon after its manufacture and before the elasticity of the upper, stretched 25 over the box toe blank, has disappeared, the box toe blank may soften to a degree admitting of the upper contracting and wrinkling the toe end of the upper of the shoe. Again 30 the box toe blank may become undesirably weak at the temperature to which it may be exposed in wear in tropical climates. When 35 these conditions present themselves, it is usually where, in the desire to produce a box toe blank that is rendered workable by a low degree of heat and a short period of heating 40 and that cools to a set condition at a comparatively slow rate, the shoe manufacturer makes use of a thermoplastic medium in the blank which softens easily and where, therefore, he takes some risk in reducing the margin of safety.

In order to avoid the occurrence of such disadvantageous results as those referred to above, the present invention in one aspect 45 relates to a method of making stiffened parts of boots and shoes which comprises placing in the upper in superposed relation a layer of thermoplastic stiffening substance and a layer of heat-resistant substance capable of being softened by a solvent which will not

affect the thermoplastic substance, lasting the upper while the substances are soft, and allowing the substances to harden. Conveniently the thermoplastic substance may be 55 waterproof and the heat-resistant substance water-soluble, since such substances are readily available and cooperate effectively to produce the desired result. As an example of one way in which the method may be practised, there may be placed in the upper at a 60 convenient stage in its manufacture a composite blank made up of a layer of fabric impregnated with a waterproof thermoplastic substance and a superposed layer of fabric impregnated with the heat-resistant, 65 water-soluble substance, the composite blank being softened before the lasting operation, if softening is required, by subjecting it to the action of steam. By employing a method 70 of this kind, the manufacturing advantages of the thermoplastic type of stiffener—such for example as the permissibility of withdrawing the last quickly—are preserved; and at the same time, adequate rigidity of 75 the box toe under exposure of the finished shoe to abnormal conditions of temperature is secured.

In other aspects, the invention relates to a stiffener comprising a layer of fabric impregnated with a waterproof, thermoplastic 80 stiffening substance and a superposed layer of fabric impregnated with a heat-resistant, water-soluble stiffening substance and to a shoe having such a stiffener incorporated 85 therein.

Referring now to the accompanying drawings,

Figure 1 is a longitudinal section of a shoe upper complete except for the stiffening of the toe portion, the upper being shown 90 mounted upon a last to the shape of which it is to be conformed.

Figure 2 is a perspective of a box toe blank.

Referring first to Figure 1, there is shown 95 a last 8 having mounted thereon in the usual manner an assembled upper of a shoe comprising the upper proper of leather, and a fabric lining. The leather upper comprises among other parts the vamp 3 and the 100

toe cap 5 which overlaps the forward edge of the vamp and is fastened to the vamp by stitches 7. The lining comprises the lining proper 11 and a so-called "plug" 9 having a contour similar to that of the toe cap and stitched at 10 to the lining.

As has been indicated above, the method of the present invention which, when employed for stiffening the toe portion of a shoe, comprises placing in the toe portion of the upper two superposed layers of stiffening substances having the stated characteristics, may be practised in various ways. For example, there is shown in Figure 2 a box toe blank which may conveniently be employed. This blank is a composite one and consists of a layer of felt or other fabric 13 impregnated with a waterproof thermoplastic substance such as a mixture of rosin and Montan wax, and a superposed adhering layer of fabric such as canvas 15 impregnated with a water-soluble adhesive such as dextrin. In practising the invention with the use of such a box-toe blank, the blank is first subjected to the action of steam which softens both layers. The soft blank is then placed in the upper between the plug and the toe cap, and the upper lasted and allowed to remain on the last until the blank has become sufficiently hard to permit the last to be withdrawn. In this connection it should be noted that, owing to the presence of the thermoplastic layer which sets immediately upon cooling, the last may be withdrawn promptly. Instead of softening the composite blank and placing the blank in the upper just prior to the lasting operation, the blank may obviously be placed or fastened in the upper at any desirable stage in the manufacture of the shoe and then softened while it is in place just before the upper is lasted. It should also be noted that the composite blank instead of being made up of two layers of impregnated fabric, may consist of a layer of impregnated fabric like 13 coated with a water-soluble adhesive, or of a layer of thermoplastic stiffening substance having a backing of impregnated canvas, or of a layer of thermoplastic stiffening substance coated with a water-soluble adhesive, the only essential feature being that there shall be placed in the toe portion of the upper of the shoe two layers of stiffening substances both in softened condition, one of which is thermoplastic and the other of which is heat resistant, as has been described.

Instead of using the composite box toe blank which has been described above, two separate blanks may be used, one being practically like the layer 13 of the composite blank, namely a piece of fabric impregnated with a thermoplastic stiffening substance, and the other being practically like the layer 15, a piece of canvas impregnated with a water-soluble stiffening substance. In case

two box toe blanks are used, they may conveniently be placed in the upper at the same stage in the manufacture of the shoe and may be softened by heat and moisture just prior to the lasting operation if at that time 70 they are hard.

Again, the method may be practised by thoroughly soaking a layer of the lining material, such as the plug 9, with a suitable solution of dextrin, placing between the lining proper and the plug a hot thermoplastic box toe blank of the well-known type and then lasting the upper so that, when the toe portion of the lasted shoe is cold and dry, the lining proper will be stuck to the thermoplastic stiffener by the adhesive action of the impregnant substance, and the plug will be stuck to the toe cap on one face and to the thermoplastic stiffener on the other by the adhesive action of the dextrin. This particular manner of practising the method is particularly advantageous for the following reason. When a thermoplastic stiffener blank is used, it is usually placed next to the toe cap. It is not ordinary practicable, however, to introduce the rear edge of such a stiffener between the overlapped portions of the toe cap and the vamp so as to butt against the connecting stitches; and consequently there is in the finished shoe no bonding between 95 these overlapped parts. As a result, said parts sometimes creep relatively to each other when the shoe is worn and develop an unsightly wrinkle or bulge adjacent to the stitch line. This undesirable occurrence is 100 prevented when a heat-resistant stiffening substance is applied in the manner last described, since more or less of the substance works into the space between the overlapped 105 portions of the toe cap and the vamp and subsequently binds them firmly together. This binding together of the overlapped parts of a toe cap and a vamp may be obtained in the case where two separate blanks are employed, as has been above indicated, by placing the blank containing water-soluble stiffening substance next to the toe cap with its rear edge projecting between the overlapped portions of toe cap and vamp, this 110 blank then acting to cement the overlapped 115 portions together. In such instance the thermoplastic blank may be placed against the plug on either side of it as may be preferred. The lasting operation which has been referred to above may be carried out in any 120 suitable manner, for example by the use of a machine of the type shown in United States Letters Patent No. 1,018,477, granted Dec. 27, 1912, upon an application filed in the name of Bröck.

Where the shoe toe is to be stiffened by two layers of material both of which have to be softened for the conforming of the upper to the shape of the last and one of which cannot be softened by heat alone or by such de- 130

gree of heat as it is safe to expose the work to there is no difficulty in securing the softening at or prior to the commencement of the operation, but, should the conforming be 5 so conducted that in the partially conformed upper the layers have to be resoftened to allow of the continuance of the conforming operation, some inconvenience may then be presented in exposing to the appropriate 10 softening influence that layer which is resistant to heat.

One way in which this may be avoided is by terminating the heat resistant layer at the 15 level, approximately, of the last bottom so that this blank by reason of its domed formation and its confinement between adjacent materials constitutes an effective stiffening agency without having any portion of it requiring to be lasted around the margin of 20 the insole and on to the shoe bottom along with the margins of the other materials. In such a case therefore if the conforming be performed by pulling-over followed by lasting proper and the shoe lies some time between the operations there is no margin of 25 the heat resistant layer requiring resoftening to that rather considerable degree which is requisite for securing the desired easy snug disposition of the materials in the vicinity of 30 the junction of the side and bottom portions of the shoe. Usually the unwonted delay between the operations would not be such that any part of the heat resistant layer extending no further towards the margin of the upper 35 materials than last indicated would have become too stiff for the easy completion of such conformation as the pulling-over operation had left undone in respect of this layer and the portion the more liable to fail to satisfy this condition (i. e. the margin nearest 40 the shoe bottom and the portion therefore most exposed to drying influences in a merely pulled-over shoe) would still in a pulled-over shoe be in a considerable measure 45 accessible to the moistening influence of the steam in the types of shoe-toe heaters in general use to resoften, between pulling-over and lasting, the toes of shoes containing thermo-plastic stiffeners.

50 An advantage arising from restricting in such a manner the area of a heat-resistant layer of stiffening material is the reduced likelihood of pincers or other shoe-engaging parts of shoe-upper conforming machinery becoming dirty and clogged with such material.

55 It is believed to be unnecessary to point out other ways in which the method of the invention may be carried out, since they are all simple variations of those which have been described.

60 In the description of the invention, the term "lasting" has been used in its broad sense as meaning the operation by which the 65 upper is conformed to the last, whether said

operation comprises one step or more than one.

Having described my invention, what I claim as new and desire to secure by Letters Patent of the United States is:—

70 1. The method of making stiffened parts of boots and shoes which comprises placing in the upper in superposed relation a layer of thermoplastic stiffening substance and a layer of heat-resistant stiffening substance capable of being softened by a solvent which will not affect the thermoplastic substance, subjecting the layer of thermoplastic substance to the action of heat and the layer of heat-resistant substance to the action of said 75 solvent, conforming the upper to a last while the substances are soft, and allowing the substances to harden.

80 2. The method of making stiffened parts of boots and shoes which comprises placing in the upper in superposed relation a layer of waterproof thermoplastic stiffening substance and a layer of heat-resistant stiffening substance capable of being softened by water, 85 softening the two substances, lasting the upper while the substances are soft, and allowing the substances to harden.

90 3. The method of making a shoe which includes placing in the upper in superposed relation two stiffeners one impregnated with a thermoplastic substance and the other with a heat-resistant substance capable of being softened by a solvent which will not affect the thermoplastic substance, softening the two substances, conforming the upper to the 95 last while the stiffeners are soft, and allowing the substances to harden.

100 4. The method of making a shoe which includes placing in the upper in superposed relation two stiffeners one impregnated with a waterproof thermoplastic substance and the other with a heat-resistant substance capable of being softened by water, subjecting the two substances to the action of steam to 105 soften them, lasting the upper while the stiffeners are soft, and allowing the substances 110 to harden.

115 5. A shoe upper prepared for lasting having in one portion thereof in superposed relation a soft layer of a waterproof thermoplastic material and a soft layer of a water-soluble material.

120 6. A shoe upper prepared for lasting having in one portion thereof in superposed relation a soft layer of thermoplastic material and a soft layer of heat-resistant material containing a solvent which does not affect the thermoplastic material.

125 7. A shoe having incorporated in the upper thereof a two-ply stiffener comprising a layer of fabric impregnated with a thermoplastic material and a layer of fabric impregnated with a heat-resistant material.

130 8. A shoe stiffener comprising a layer of fabric impregnated with a waterproof ther-

moplastic stiffening substance and a super-
posed layer of fabric impregnated with a
heat-resistant water-soluble stiffening sub-
stance.

5 9. A shoe upper comprising a vamp and a
toe cap fastened together in overlapped rela-
tion and having incorporated in said upper a

layer of thermoplastic material and a layer
of water soluble material of which one of
said layers projects between the overlapped 10
portions of said vamp and toe cap.

In testimony whereof I have signed my
name to this specification.

FRED RICKS.
